METHOD OF OPERATING STEAM-BOILER ECONOMIZERS.

1,285,201.

Specification of Letters Patent.

Patented Nov. 19, 1918.

Application filed December 8, 1914. Serial No. 876,016.

To all whom it may concern:

Be it known that we, DAVID S. JACOBUS and HERMAN C. HEATON, citizens of the United States, residing, respectively, at Jersey City, in the county of Hudson and State of New Jersey, and at Chicago, in the county of Cook, in the State of Illinois, have invented certain new and useful Improvements in Methods of Operating Steam-Boiler Economizers, of which the following is a specification.

Our invention relates to that type of combined boilers and economizers wherein moisture from the flue gases is condensed on the economizer or part thereof.

The moisture which is thus condensed from the flue gases in the economizer is derived from three sources—(1) the moisture in the air entering the furnace; (2) the moisture in the fuel; and (3) the moisture produced through the combustion of the hydrogen component of the fuel. The amount of moisture which may be condensed from the flue gases depends upon the temperature of the entering feed water, and the temperature of the gases. With a feed water temperature of, say, 80° F., entering that part of the economizer which is subjected to the coldest gases, the dew point will be reduced to 80° F. as a minimum, and the amount of moisture carried off by the flue gases will correspond to the actual dew point which may be, say, 90° F. The volume of the flue gases is approximately that of the entering air and, therefore, under the assumed conditions, if the air entering the furnace is saturated at 90° F., there would be substantially no loss of latent heat through the carrying off of the moisture in the flue gases, as the total amount of latent heat in the vapor would be about the same in each case. The general purpose of the invention, therefore, is the saturation of the air entering a furnace with moisture so that this moisture will carry enough latent heat into the system to offset the usual loss through the heat in the vapor which escapes with the flue gases. Any additional vapor over this amount will be available for condensation upon the economizer tubes and will add to the heat imparted and to the efficiency.

In order to enable our invention to be

practised, that part of the economizer where the moisture is condensed must be arranged so that it will resist the corrosive action of the moisture and acid fumes. To accomplish this the part of the economizer in question must be constructed of acid-resisting material, or, if constructed of tubes that will not be acid-resisting, these tubes must be coated with a material which will resist the acid. The economizer system described in the application of David S. Jacobus, Serial No. 784,315, filed August 12, 1913, is especially applicable for the purpose and such an economizer is shown in the accompanying drawing, which is diagrammatic and shows that part of a steam boiler plant necessary to illustrate the invention. In this drawing the numeral 1 designates a boiler of standard design, shown as fired by a chain grate stoker 2. The course of the gases through the boiler to the outlet flue 3 is indicated by the arrows. In this flue is placed an economizer, comprising a high pressure stage 4, and a low pressure stage having three separated banks of tubes, 5, 6 and 7. The high pressure stage is subjected to the hottest gases and the low pressure stage to the coldest gases, the gases leaving the economizer through an exhaust fan 8 and discharging into the stack 9. The present invention is not concerned with the particular construction of the economizer. It may be stated in general, however, that the high pressure stage is made up of wrought iron or wrought steel tubes expanded into wrought metal headers or boxes. The low pressure banks may be made up of cast iron tubes connected to cast iron headers or boxes and covered with an acid-resisting material or tubes other than cast iron may be used. The casing has doors 10 leading to the spaces between the banks for the purpose of providing access to the tubes. We have shown scrapers 11 for removing any deposit which may collect upon the tubes. Below each bank is a pit 12 into which the deposit is permitted to accumulate. These pits also receive the condensed vapor from the flue gases. The feed water from the hot well, or other source, is delivered to bank of tubes 7 of the low pressure stage of the economizer through a pipe 13 and from said bank it flows downward through a pipe 14 to the

lower headers of bank 6. From the latter bank the water flows through pipe 15 to the lower headers of bank 5, and from the latter bank the water is delivered through pipe 16 to a tank 17. The tank 17 is provided with a connection 18 to a dry vacuum pump to maintain the pressure in the tank below that of the atmosphere to assist in the removal of the air and gases from the water heated in the low pressure stage of the economizer. The tank 17, if used as a heater, as disclosed in copending application of Herman C. Heaton, Serial No. 876,005, dated December 8, 1914, will be provided 15 with a connection 19 to conduct to the tank the exhaust steam from the auxiliaries or from any other source in the plant.

From the tank 17 the water is withdrawn through a pipe 20 to a pump 21, and by 20 the latter forced through pipe 22 into and through the high pressure stage 4 of the economizer against the boiler pressure and is delivered from the economizer through pipe 23 to the steam and water drum 24.

25 The addition of moisture to the air entering the furnace may be accomplished in various ways, as, for example, by spraying water into the air. In the drawing the air entering the furnace is shown as coming 30 from a tower or chamber 25, used for cooling the circulating water from the condensers, or what is ordinarily known as a cooling tower. The air enters the tower through an opening 26 and passes upward in the direction indicated by the arrows to a blower 27 by which the moistened and somewhat heated air is forced through flue 28 to the space 35 below the grate. In order to obtain an increase in the efficiency, the moisture introduced with the air should be secured through some source of waste heat, and a cooling tower meets this requirement. Where atmospheric air is introduced to a cooling tower there will be an addition of moisture to the 40 air, even if the latter is saturated upon entering the tower. This is due to the rise in temperature of the air on coming in contact with the hot water spray. Any other method may be adopted for imparting the necessary 45 amount of moisture to the air for combustion such, for example, as a perforated steam pipe 30 discharging below the grate, the steam being obtained from some waste 50 source. While we have described the invention in connection with a two stage econo-

60 mizer, it is obvious that it may be practised with a single stage or ordinary economizer providing the tubes on which the moisture condensers are made so that they will resist the acid fumes.

65 What we claim and desire to secure by Letters Patent of the United States is:—

1. In the operation of a power plant the steps consisting of supplying moisture, heated by waste heat from said power plant, to 70 the air entering a boiler furnace to a sufficient extent to cause condensation of at least a portion of said moisture on an economizer, and then passing the flue gases over an economizer in the waste flue, feeding 75 water through said economizer to the boiler, and cooling the gases down to a point where at least a portion of the introduced moisture will be condensed on the economizer tubes.

2. In the operation of a power plant the steps consisting of supplying at least a portion of the heated condenser water to the air entering a boiler furnace to a sufficient extent to cause condensation of at least a 80 portion of said moisture on an economizer, and then passing the flue gases over an economizer in the waste flue, feeding water through said economizer to the boiler, and cooling the gases down to a point where at 85 least a portion of the introduced moisture will be condensed on the economizer tubes.

3. In the operation of a power plant the steps consisting of bringing cooling water from a condenser into intimate contact with 90 a current of air, sucking the current of air forwardly and forcing it into a boiler furnace, passing the waste gases from the boiler furnace over an economizer, feeding water through said economizer to the boiler, and 95 condensing at least a portion of the introduced moisture on said economizer.

In testimony whereof we have hereunto signed our names in the presence of the sub-scribing witnesses.
